JOSEPH C. TOMASZEWSKI, OF CHICAGO, ILLINOIS, ASSIGNOR OF ONE-FOURTH TO JOHN TOMASZEWSKI AND ONE-FOURTH TO ADAM FRANCZEK, BOTH OF CHICAGO, ILLINOIS.

COMBINED CLUB AND FIREARM.

1,160,343.

Specification of Letters Patent. Patented Nov. 16, 1915.

Application filed June 25, 1915. Serial No. 36,260.

To all whom it may concern:

Be it known that I, JOSEPH C. TOMASZEWSKI, a citizen of the United States, and a resident of the city of Chicago, county of Cook, and State of Illinois, have invented a certain new and Improved Combined Club and Firearm, of which the following is a specification.

My invention relates to a combined club and firearm designed for use primarily by 10 policemen, and has for its object, the production of a device of this character which will be of simple construction and efficient in use.

Other objects will appear hereinafter. The invention consists in the combinations and arrangements of parts hereinafter described and claimed.

The invention will be best understood by 20 reference to the accompanying drawing forming a part of this specification, and in which,

Figure 1 is a side elevation of a combined club and firearm embodying the invention, 25 Fig. 2 is a central longitudinal section of the device, showing the plunger thereof advanced to nearly firing position, Fig. 3 is a central longitudinal section of the rearward end portion of the device showing the plunger locked in "safety" position, and Fig. 4 is an enlarged detail section taken on line x—x of Fig. 2.

The preferred form of construction, as 35 illustrated in the drawing, comprises an elongated tubular body 1 at the front end of which is provided a barrel member 2, the rearward end of member 2 being in threaded connection with said body so as to permit of ready removal. Formed in the member 2 40 is an axial bore 3 in the rearward end of which the cartridge 4 is adapted to be arranged, the flange of the cartridge being adapted to abut the rearward end of said member 2. It will be seen that insertion of 45 a cartridge into the rearward end of the member 2 may be readily and easily effected upon removal of the latter. When the cartridge is positioned in the member 2, the same is securely clamped in position between the rearward end of member 2 and a member 5 which is threaded in the front end of body 1. Arranged in the front end of body 1 is a firing pin 6, the front end of which is slidably mounted in member 5, 55 the rearward end of said firing pin being

slidably mounted in a member 7 which is securely fastened as by screws in the member 1. Interposed between the member 5 and a collar 8, formed upon the firing pin, is a comparatively light helical compression 60 spring 9 which serves to normally hold the firing pin in retracted position. When said firing pin is in retracted position, the rearward end thereof projects slightly beyond the rearward side of member 7 for engagement by the front end of a plunger 10 slidably mounted in the rearward end of body 1. At the front end of plunger 10 is provided a head 11 between which and a member 12, secured in the rearward end of body 70 1, is interposed a helical compression spring 13, said spring being adapted, upon release of the plunger from retracted position, to thrust the plunger forwardly into engagement with the firing pin 6. Provided upon 75 the rearward end of plunger 10 is a handle 14 through the medium of which said plunger may be manually retracted.

Provided in the body 1, the same also projecting through the member 12, is a screw 80 or threaded pin 15, the inner end of which engages with a slot formed in the adjacent side of plunger 10. Said slot is of substantially H-shape consisting of two longitudinally extending spaced portions 16 and 17, 85 the former of which is longer than the latter, and a transversely extending connecting portion 18. The arrangement is such that, when the pin 15 is in engagement with the slot portion 16, the plunger will be 90 permitted to advance into operative relation with the firing pin 6. The plunger is not permitted to advance into operative relation with the firing pin, when the pin 15 is in engagement with the slot portion 17, 95 the latter being of insufficient length to permit of this movement. Loosely threaded upon the plunger at the point of registration thereof with the rearward end of body 1 is a collar 19 having an outwardly projecting 100 flange 20 which is adapted to engage against the rearward end of said body, as clearly shown in Fig. 3. Said collar is provided as a means of locking the plunger in "safety" position, it being clear that by positively rotating said collar upon the plunger, with the pin 15 engaging in the slot portion 17, said plunger may be moved rearwardly until said pin 15 engages against the front end of the slot portion 17, as clearly shown in Fig. 3. 110

When this position is reached, it will be seen that the collar 19 will serve to lock the plunger against forward movement and the pin 15 will serve to lock the same against rearward movement, thus positively locking the plunger against any relative movement. In order to release the plunger from "safety" position, for firing, it is first required to unscrew the collar 19 to the position shown in Fig. 2. When this is done, the plunger may be advanced into a position in which the transversely extending slot portion 18 registers with the pin 15. This having been done, the plunger is rotated so as to engage the pin 15 with slot portion 16. This position having been reached, in order to fire, it is only necessary to retract the plunger and suddenly release the handle. Upon release of the handle, the spring 10 will thrust the plunger forwardly into engagement with the firing pin 6, the latter in turn being thrust forwardly into engagement with the cartridge, effecting explosion and firing of the latter. When the plunger is locked in "safety" position, it will be seen that the device constitutes simply an ordinary policeman's club. If desired, the parts 1 and 2 may be covered with a casing of leather or other suitable protecting material, as shown.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A device of the class described comprising an elongated tubular body; a cartridge barrel provided at one end of said body adapted to accommodate a cartridge at its rearward end; a firing pin arranged in operative relation with said barrel; a light spring coöperating with said firing pin for normally holding the same in retracted position; a plunger slidably mounted in said body for coöperation with said firing pin; a spring coöperating with said plunger for thrusting the same forwardly, when said plunger is released from retracted position; an exteriorly positioned handle on said plunger for retracting the same; and means for releasably locking said plunger in "safety" position, said means comprising two stop elements one of which is adapted to lock said plunger against forward movement and the other of which is adapted to lock said plunger against rearward movement, substantially as described.
2. A device of the class described com-

prising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 75

3. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 80

3. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 85

3. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 90

3. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 95

3. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 100

4. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 105

4. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 110

4. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 115

4. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 120

4. A device of the class described comprising an elongated tubular body; a cartridge barrel provided at one end of said body adapted to accommodate a cartridge at its rearward end; a firing pin arranged in operative relation with said barrel; a plunger slidably mounted in said body for coöperation with said firing pin; a spring coöperating with said plunger for thrusting the same forwardly, when said plunger is released from retracted position; an exteriorly positioned handle on said plunger for retracting the same; means for releasably locking said plunger in "safety" position, said means comprising a pin mounted in said body engaging at its inner end with a slot provided in said plunger for limiting rearward movement of said plunger; and a stop member adjustably mounted on said plunger for locking the latter against forward movement, substantially as described. 125

pin is engaged with the longer one of said longitudinal slot portions, substantially as described.

5. A device of the class described comprising an elongated tubular body; a cartridge barrel provided at one end of said body adapted to accommodate a cartridge; a plunger slidably mounted in said body for coöperation with said firing pin; a spring 10 coöperating with said plunger for thrusting the same forwardly when said plunger is released from retracted position; an exteriorly positioned handle on said plunger for retracting the same; means for releasably 15 locking said plunger in "safety" position, said means comprising a pin mounted in said body having its inner end engaging a slot provided in said plunger, said slot consisting of two spaced longitudinally extending 20 portions of different lengths and a transversely extending connecting portion, said plunger being permitted to advance to operative relation with said firing pin only when said last mentioned pin is engaged with the 25 longer one of said longitudinal slot portions; and means on said plunger for locking the same in a position in which said last mentioned pin is engaged with the front end of one of said longitudinal slot portions, 30 substantially as described.

6. A device of the class described comprising an elongated tubular body; a cartridge barrel provided at one end of said body adapted to accommodate a cartridge; 35 a firing pin arranged in operative relation with said barrel; a plunger slidably mounted in said body for coöperation with said firing pin; a spring coöperating with said plunger for thrusting the same forwardly 40 when said plunger is released from retracted position; an exteriorly positioned handle on said plunger for retracting the same; means for releasably locking said plunger in

"safety" position, said means comprising a pin mounted in said body having its inner 45 end engaging a slot provided in said plunger, said slot consisting of two spaced longitudinally extending portions of different lengths and a transversely extending connecting portion, said plunger being permitted to advance to operative relation with said firing pin only when said last mentioned pin is engaged with the longer one of said longitudinal slot portions; and a nut 50 threaded on said plunger for locking the same in a position in which said last mentioned pin is engaged with the front end of one of said longitudinal slot portions, substantially as described.

7. A device of the class described comprising an elongated tubular body; a cartridge barrel provided at the front end of said body adapted to accommodate a cartridge; a firing pin arranged in operative 60 relation with said barrel; a plunger slidably mounted in said body for coöperation with said firing pin; a spring coöperating with said plunger for thrusting the same forwardly when said plunger is released from retracted position; an exteriorly positioned 65 handle on said plunger at the rearward end of said body for retracting said plunger; and means for releasably locking said plunger in "safety" position, said means comprising a nut threaded on said plunger 70 adapted to be adjusted to prevent said plunger advancing into operative relation with said firing pin, substantially as described.

In testimony whereof I have signed my name to this specification in the presence of 80 two subscribing witnesses.

JOSEPH C. TOMASZEWSKI.
